TRIPLE ACTING PUMP

William H. Zehner, Ashland, Ohio, assignor to The
F. E. Myers & Bro. Co., Ashland, Ohio, a cor-
poration of Ohio

Application August 11, 1939, Serial No. 289,649

12 Claims.

(Cl. 103—4)

This invention relates to a triple acting pump which constitutes an improvement over what is commonly known as a double acting pump in that it will deliver a greatly increased amount of liquid with a given size of pumping equipment over that delivered by a double acting pump. The pump described herein is also characterized, in a preferred embodiment, by the fact that the working parts can be removed upwardly through the well pipe by simply pulling upwardly on the sucker rod.

It is the principal object of this invention to provide a pump having two plungers, each of which delivers liquid both on the upstroke and on the downstroke.

Another object is to provide a pump of the foregoing type wherein all of the working parts can be removed from the well without pulling the well pipe, by merely pulling upwardly on the pump rod.

Another object is to provide a pump of the foregoing type wherein the two plungers are connected by a slide rod, means being provided in the surrounding casing for fluid communication between the chambers formed by the two plungers.

Still another object is to provide a modified form of pump of the foregoing type wherein all of the working parts except the foot or check valve are removed upwardly by pulling on the pump rod and wherein the check valve is removed upwardly by again inserting a portion of the first removed assembly into contact with the check valve; in this modification, the assembly is supported by a tapered seat, intermediate of the two plungers, whereas in the preferred embodiment, the assembly is supported by a tapered seat located below the foot or check valve.

Still other objects will more fully hereinafter appear.

Reference is made under Rule 43 to my co-pending applications Ser. Nos. 289,647 and 289,648, filed of even date herewith.

Referring to the accompanying drawing:

Figure 1 is a vertical section of a pump embodying the principles of the present invention.

Figure 2 is a vertical section on the line 2—2 of Figure 1.

Figure 3 is a vertical section of a modified form 50 of the invention.

Figure 4 is a vertical section on the line 4—4 of Figure 3.

Referring to the drawing in detail, and first to the embodiment shown in Figures 1 and 2, 55

reference numeral 1 designates an upper cylinder and reference numeral 2 designates a lower cylinder. Cylinder 2 is of smaller external diameter than the internal diameter of cylinder 1, 5 so that cylinder 2 may be removed upwardly through cylinder 1. Surrounding upper cylinder 1 is an upper casing 5 and surrounding cylinder 2 is a lower casing 6. Casings 5 and 6 are joined by an intermediate casting 3 which will be described below in greater detail. Upper cylinder 1 and upper casing 5 are threadably connected to an upper collar 8 which threadably engages a well pipe 26, which is preferably of larger internal diameter than upper cylinder 1. Upper cylinder 1 rests in a stepped portion 27 formed at the inside 10 of the upper end of casting 3. The interior of casting 3 is of the same diameter as the inside of upper cylinder 1.

Lower cylinder 2 is threadably engaged with a 15 check valve housing 28 which is in the form of a collar attached to a tapered collar 29. Tapered collar 29 is supported in a tapered seat 9 formed on the interior of a lower collar 30. Collar 30 is threadably engaged with the lower end of casing 6, and the upper end of casing 6 is threadably engaged with the lower portion of casting 3.

An upper plunger designated generally as 31 20 reciprocates in upper cylinder 1. A pump rod 32 is threadably engaged with plunger 31. Plunger 31 is provided with sealing means 11, which seals it with respect to cylinder 1. Plunger 31 is further provided with a cylindrical passageway 33 which communicates with the space A formed below plunger 31 by means of ports 24, 25 and passageway 33 is adapted to communicate with space D formed above plunger 31 by means of check valve 10, which is normally held in closed position by a spring 34.

A lower plunger 35 reciprocates in lower cylinder 2. Lower plunger 35 is provided with sealing means 12, which seals it with respect to cylinder 2. Lower plunger 35 divides lower cylinder 2 into an upper chamber B and a lower chamber C. Lower plunger 35 is connected with upper plunger 31 by a rod 13, so that these plungers move together. Check valve 18 is provided below chamber C, and serves to admit fluid upwardly into chamber C but to prevent liquid from passing downwardly from chamber C. Check valve 18 is normally held closed by a spring 36. Check valve housing 28 is provided with passageways 7 which are adapted to allow fluid communication between chamber C and chamber 37, which is formed between cylinder 2 and casing

6. Passageways 7 further allow liquid to pass upwardly from below the check valve 18 into chamber 37.

Intermediate casting 3 is provided with ports 38 which communicate with passageways 25 provided in a collar 39 which is part of the intermediate sealing assembly. Passageways 25 communicate with chamber B through a check valve 17 which is normally held closed by a spring 40. The intermediate sealing assembly is sealed with respect to casting 3 by sealing means 41 and 42.

Chamber B is adapted to be placed in fluid communication with chamber 22 formed between casing 5 and cylinder 1 by means of an annular passageway 20 formed between collar 39 and rod 13. This annular passageway 20 is in communication with passageways 43 which are formed in a collar 44 threadably engaged with collar 39. Passageways 43 are normally sealed by a check valve 16 which is normally held closed by a spring 45. When valve 16 is open, liquid may freely pass from passageways 43 into vertical passageways 21 formed in casting 3. Passageways 21 are in free communication with chamber 22 formed between casing 5 and cylinder 1. Chamber 22 is in free fluid communication with space D by means of ports 23 provided in the upper portion of casing 1 at a point above the upper reciprocating position of plunger 31.

Threadably engaged with collar 44 is another collar 46 which carries sealing means 15 which seal the intermediate assembly with respect to the inside wall of casting 3. The intermediate assembly is also provided with sealing means 14 which seals the same with respect to reciprocating rod 13.

Fluid communication between chamber 37 and space A is provided by means of vertical passageways 19 formed in casting 3 (see Figure 2). These passageways 19 discharge through ports 47 into chamber A.

In assembling the mechanism, assuming that the well pipe 26 to which cylinder 1, casings 5 and 6, intermediate casting 3 and tapered collar 30 are all assembled, has been lowered into the position shown in the drawing, the slideable working assembly comprising upper plunger 31, lower plunger 35, lower cylinder 2, check valve assembly 28 and the intermediate sealing and valve assembly, all attached to the sucker rod 32, is lowered into operative position where collar 29 is firmly seated in the tapered seat 9 of collar 30, thus supporting the assembly in its operative position. Should it subsequently be desired to remove the working parts, the pump rod 32 is pulled upwardly until lower plunger 35 strikes the lowermost portion of the intermediate sealing assembly, whereupon the assembly is raised as a unit up through casting 3, upper cylinder 1, into well pipe 26.

The operation of the pump of the present invention is as follows: On the upstroke, lower plunger 35 sucks liquid upwardly through valve 18 into space C while upper plunger 31 sucks liquid upwardly into space A through valve 18, ports 7, chamber 37 and passageways 19. At the same time, upper plunger 31, because valve 10 is closed, lifts the liquid in space D upwardly into the well pipe 26, and lower plunger 35, because valve 17 is closed, forces liquid from space B through passageway 20, ports 43, valve 16, passageways 21, chamber 22 and ports 23 into space D, and thus into well pipe 26. On the downstroke, foot or check valve 18 is closed and lower

plunger 35 forces liquid from space C through passageways 7, chamber 37, passageways 19, ports 41, space A, ports 24, passageway 33 and upper plunger valve 10 into space D. At the same time, upper plunger 31 forces liquid from space A below it, through ports 24, passageway 33 and valve 10 into space D. Simultaneously, lower plunger 35, because of valve 16 being closed, draws liquid from the exterior of the pump through ports 38, passageways 25, and valve 17 into space B, thereby filling space B preparatory to the upstroke.

In the modification shown in Figures 3 and 4, intermediate casting 3a is tapered internally as at 4, and receives a correspondingly tapered collar 39a provided in the intermediate sealing assembly. By reason of the tapered seat thus provided, the necessity for the employment of sealing means 41 and 42 utilized in the first modification is dispensed with. The mode of operation is precisely the same as for the embodiment of Figures 1 and 2. The lower cylinder 2a is threadably engaged with the inside of the lower portion of casting 3 and consequently is not removable upwardly. Lower plunger 35a is of smaller diameter than the lower plunger of the modification of Figures 1 and 2, so that it is removable upwardly through the tapered seat 4. In this way, the working assembly is supported by the intermediate casting 3a. Check valve 18 is carried in an assembly which is not removable upwardly when the working assembly is removed from the cylinder by pulling upwardly on pump rod 32. The lower end of casing 2a serves to guide the check valve assembly. When it is desired to remove the working parts from the cylinder, the pump rod 32 is first pulled upwardly, displacing collar 39a from tapered seat 4. When the assembly has been pulled all the way to the surface, the lower plunger 35a is unthreaded, the intermediate sealing, valve and supporting assembly is removed from rod 13, and lower plunger 35 is then replaced, the upper and lower plungers inserted by means of pump rod 32 again into the cylinder until inwardly formed threads 48 formed on the lower portion of plunger 35a contact threads 49 formed on collar 28a of the check valve assembly. The pump rod is then rotated to cause engagement of threads 48 and 49 and is then pulled upwardly, bringing the check valve assembly with it.

It will be understood that I desire to comprehend as within my invention such modifications as will be necessary to adapt the same to varying conditions and uses.

Having thus fully described my invention, what I claim as new and desire to secure by Letters Patent is:

1. In a pump, an upper cylinder, an upper plunger reciprocating therein, means carried by said plunger for allowing fluid to pass upwardly therethrough from the space therebelow, an upper casing surrounding said upper cylinder, and forming a chamber therebetween, means providing free fluid communication between the chamber thus formed and the delivery space above said upper plunger, a lower cylinder, a lower plunger reciprocating therein, inwardly opening check valve means therebelow leading into the space therebelow, inwardly opening check valve means thereabove leading into the space thereabove, a lower casing surrounding said lower cylinder and forming a chamber therebetween, said last-named chamber being in

free fluid communication with said space below said lower plunger, common means connecting said upper and lower casings and having a passageway providing free fluid communication between said chamber formed between said lower casing and cylinder and said space below said upper plunger and having a passageway connecting with said chamber formed between said upper casing and cylinder and adapted to be placed in communication with said space above said lower plunger, and upwardly opening check valve means controlling the passage of fluid through said last-named passageway.

2. In a pump, a reciprocating upper plunger, means carried by said plunger for allowing fluid to pass upwardly therethrough from the space therebelow, a reciprocating lower plunger, means forming a cylinder for each of said plungers, means connecting said cylinders, stationary sealing means positioned adjacent said cylinder connecting means and between said plungers, means connecting said plungers so that they reciprocate together, means disposed outwardly of said lower plunger providing free fluid communication between the space directly below said lower plunger and the chamber formed below said upper plunger, means disposed outwardly of said upper plunger in free fluid communication with the space above said upper plunger and with the space above said lower plunger valve means for permitting ingress of fluid to the space above said lower plunger, valve means for permitting egress of fluid from the space above said lower plunger to said last mentioned fluid communication means, and check valve means for allowing fluid to enter the spaces below said plungers.

3. In a pump, an upper cylinder, an upper plunger reciprocating therein, check valve means for allowing fluid to pass from the space below said plunger to the space thereabove, an upper casing surrounding said upper cylinder and forming an upper chamber therebetween, means connecting said upper chamber to the space above said plunger, a lower cylinder, a lower plunger reciprocating therein, a lower casing surrounding said lower cylinder and forming a lower chamber therebetween, means connecting said lower chamber to the space below said lower plunger, means connecting said plungers so that they reciprocate together, means joining said upper and lower casings, said last-named means being provided with passageways providing fluid communication between said lower chamber and the space below said upper plunger and with passageways in free fluid communication with said upper chamber, and with the space above said lower plunger, valve means for permitting ingress of fluid to the space above said lower plunger, and check valve means for allowing fluid to pass from said space above said lower plunger into said upper chamber.

4. In a pump, an upper cylinder, an upper plunger reciprocating therein, check valve means for allowing fluid to pass from the space below said upper plunger to the space thereabove, an upper casing surrounding said upper cylinder and forming an upper chamber therebetween, means connecting said chamber to the space above said plunger, a lower cylinder, a lower plunger reciprocating therein, a lower casing surrounding said lower cylinder and forming a lower chamber therebetween, means connecting said lower chamber to the space below said lower plunger, means connecting said plungers so that they reciprocate together, means joining

said upper and lower casings, said last-named means being provided with passageways providing fluid communication between said lower chamber and the space below said upper plunger, with passageways in free fluid communication with said upper chamber, and with ports communicating with the exterior of the pump, stationary means positioned within the means joining said upper and lower casings arranged intermediate said plungers and provided with passageways connecting said ports with the space above said lower plunger and with passageways connecting said space above said lower plunger with the second-named passageways in said means joining the upper and lower casings, and check valve means for allowing fluid to pass upwardly from said space above said lower plunger through said last-named passageways into said second-named passageways.

5. In a pump, in combination, a well pipe, a stationary assembly attached thereto which comprises an upper cylinder, an upper casing therearound forming an upper chamber therebetween in communication with said well pipe, a lower casing, and intermediate means connecting said casings, a pump rod, and a slidable working assembly disposed within said stationary assembly comprising an upper plunger attached to said pump rod and adapted to reciprocate in said upper cylinder, a lower cylinder adapted to normally rest within said lower casing and to form a lower chamber therebetween, a lower plunger adapted to reciprocate in said lower cylinder, a rod connecting said plungers so that they reciprocate together, and stationary means at the upper end of said lower cylinder adapted to be normally disposed opposite said intermediate means and to separate and seal said upper and lower cylinders, said working assembly being removable as a unit upwardly out of said stationary assembly by pulling upwardly on said pump rod, said intermediate means having a passageway connecting said lower chamber with the space below said upper plunger, said stationary means having a passageway adapted to interconnect said space above said lower plunger and said upper chamber, check valve means for allowing fluid to pass through said last-named passageway into said upper chamber, and check valve means for allowing fluid to pass into said space above said lower plunger, check valve means for allowing fluid to enter the spaces below said plungers, and check valve means for allowing fluid to pass from the space below said upper plunger into the delivery space thereabove.

6. In a pump, in combination, a well pipe, a stationary assembly attached thereto which comprises an upper cylinder, an upper casing therearound forming an upper chamber therebetween in communication with said well pipe, a lower casing, intermediate means connecting said casings, and internally downwardly tapered means mounted on the lower end of said lower casing, a pump rod, and a slidable working assembly disposed within said stationary assembly comprising an upper plunger attached to said pump rod and adapted to reciprocate in said upper cylinder, a lower cylinder adapted to normally rest within said lower casing and to form a lower chamber therebetween, a lower plunger adapted to reciprocate in said lower cylinder, a rod connecting said plungers so that they reciprocate together, stationary means at the upper end of said lower cylinder adapted to be normally dis-

posed opposite said intermediate means and to separate and seal said upper and lower cylinders, and externally downwardly tapered means mounted on the lower end of said lower cylinder and adapted to be seated in said internally tapered means and to thereby support said working assembly, said working assembly being removable as a unit upwardly out of said stationary assembly by pulling upwardly on said pump rod, said intermediate means having a passageway connecting said lower chamber with the space below said upper plunger, said stationary means having a passageway adapted to interconnect said space above said lower plunger and said upper chamber, check valve means for allowing fluid to pass through said last-named passageway into said upper chamber, and check valve means for allowing fluid to pass into said space above said lower plunger, check valve means for allowing fluid to enter the spaces below said plungers, and check valve means for allowing fluid to pass from the space below said upper plunger into the delivery space thereabove.

7. In a pump, in combination, a well pipe, a stationary assembly attached thereto which comprises an upper cylinder, an upper casing therearound forming an upper chamber therebetween in communication with said well pipe, a lower cylinder, a lower casing therearound forming a lower chamber therebetween, and internally downwardly tapered intermediate means connecting said casings, a pump rod, and a slideable working assembly disposed within said stationary means and comprising an upper plunger attached to said pump rod and adapted to reciprocate in said upper cylinder, a lower plunger adapted to reciprocate in said lower cylinder, a rod connecting said plungers so that they reciprocate together, and stationary means located intermediate said upper and lower cylinders and tapered externally downwardly to correspond with the taper on said intermediate means and adapted to be normally seated within said intermediate means and to thereby support said working assembly, said working assembly being removable as a unit upwardly out of said stationary assembly by pulling upwardly on said pump rod, said intermediate means having a passageway connecting said lower chamber with the space below said upper plunger, said stationary means having a passageway adapted to interconnect said space above said lower plunger and said upper chamber, check valve means for allowing fluid to pass through said last-named passageway into said upper chamber, and check valve means for allowing fluid to pass into said space above said lower plunger, check valve means for allowing fluid to enter the spaces below said plungers, and check valve means for allowing fluid to pass from the space below said upper plunger into the delivery space thereabove.

8. In a pump, an upper cylinder, an upper casing therearound forming an upper chamber therebetween, an upper plunger in said cylinder, a lower cylinder, a lower casing therearound forming a lower chamber therebetween, a lower plunger in said lower cylinder, intermediate means connecting said casings and provided with ports connecting to a point exterior of said pump, with passageways communicating with said upper chamber, and with second passageways connecting said lower chamber with the space below said upper plunger, stationary means intermediate said upper and lower cylinders and having

third passageways connecting said ports with the space above said lower plunger, and fourth passageways connecting said space above said lower plunger with said first-named passageways, check valve means for allowing fluid to pass through said third passageways into said space above said lower plunger, check valve means for allowing fluid to pass from said space above said lower plunger through said fourth and first-named passageways into said upper chamber, said lower chamber communicating with the space below said lower plunger, means connecting said upper chamber to the delivery space above said upper plunger, check valve means for allowing fluid to pass from the space below said upper plunger to said delivery space, means rigidly connecting said plungers, and check valve means for allowing fluid to enter the spaces below said plungers.

9. In a pump, an upper cylinder, an upper casing therearound forming an upper chamber therebetween, an upper plunger in said cylinder, a lower cylinder, a lower casing therearound forming a lower chamber therebetween, a lower plunger in said lower cylinder, intermediate means connecting said casings and provided with ports connecting to a point exterior of said pump, with passageways communicating with said upper chamber and with passageways connecting said lower chamber with the space below said upper plunger, and stationary means intermediate said upper and lower cylinders and having check valved passageways connecting said ports with the space above said lower plunger, and check valved passageways connecting said space above said lower plunger with said passageways communicating with said upper chamber, means connecting said upper chamber to the delivery space above said upper plunger, check valve means for allowing fluid to pass from the space below said upper plunger to the delivery space, means rigidly connecting said plungers, means connecting said lower chamber to the space below said lower plunger, and check valve means for allowing fluid to enter the spaces below said plungers.

10. In a pump, an upper cylinder, an upper plunger reciprocable therein, check valve means allowing fluid to pass from the space below said plunger to the delivery space thereabove, means forming an upper chamber around said cylinder and in communication with said delivery space, a lower cylinder, a lower plunger constructed and arranged to prevent the passage of fluid therethrough reciprocable therein, means connecting said cylinders, stationary sealing means positioned between said cylinders and within said connecting means, means forming a lower chamber around said lower cylinder and in communication with the space below said lower plunger, means connecting said lower chamber to the space below said upper plunger, means rigidly connecting said plungers, means adapted to connect the space above said lower plunger to said upper chamber, check valve means for allowing fluid to pass through said last-named means to said upper chamber, check valve inlet means for allowing fluid to enter the spaces below said plungers and check valved inlet means for allowing fluid to enter from a point exteriorly of the pump into the space above said lower plunger.

11. In a pump, an upper plunger, an upwardly opening check valve carried thereby for allowing fluid to pass therethrough, a lower plunger con-

structed and arranged to prevent the passage of fluid therethrough, means forming a cylinder for each of said plungers, means exterior of said plungers for providing fluid communication between the spaces directly below said plungers, means for sealing the bottom of the space below said upper plunger, means for sealing the top of the space above said lower plunger, check valve means for allowing fluid to be drawn by said upper and lower plungers into the space therebelow, means connecting said plungers to reciprocate together, stationary check valve means for allowing fluid to pass into the space above said lower plunger, means exterior of said plungers for providing fluid communication between the space above said lower plunger and the delivery space above said upper plunger, and check valve means for allowing fluid to pass through said last-named means from the space above said lower plunger into the delivery space 20 above said upper plunger.

12. In a pump, an upper cylinder, an upper plunger therein, a lower cylinder, a lower plunger therein constructed and arranged to prevent the passage of fluid therethrough, means sealing the lower end of said upper cylinder and the upper end of said lower cylinder, check valve means in said upper plunger for allowing fluid to pass upwardly therethrough into the delivery space thereabove, fluid-tight means rigidly connecting said plungers, means for permitting said lower plunger to suck fluid into the space above said lower plunger from outside the pump on the downstroke, means for permitting said lower plunger to force fluid from said space above said lower plunger into said delivery space on the upstroke, means connecting the spaces directly below said plungers, and check valve means below said lower plunger for admitting fluid to the space therebelow.

WILLIAM H. ZEHNER.
